UNITED STATES PATENT OFFICE.

AVARY B. CARROLL, OF NORFOLK, VIRGINIA.

SAFETY-RAZOR.

1,241,921.

Specification of Letters Patent.

Patented Oct. 2, 1917.

Application filed August 23, 1916. Serial No. 116,523.

To all whom it may concern:

Be it known that I, AVARY B. CARROLL, a citizen of the United States, and resident of Norfolk, in the county of Norfolk and State of Virginia, have invented certain new and useful Improvements in Safety-Razors, of which the following is a specification.

The present invention relates to the art of cutlery and has particular reference to new and useful improvements in safety razors.

The primary object of my invention is to provide a safety razor which is cheap to manufacture, easy and safe to use and effective in operation.

Another object of my invention is to provide a safety razor in which the cutting elements are so arranged that a draw cut is provided tending to greatly enhance the efficiency of such razors and render the same more safe.

A further object of my invention is to provide a safety razor having new and improved means for supporting a plurality of the blades for coöperation in shaving.

A still further object of my invention is to provide a safety razor of the class described having a frame for supporting a plurality of blades at proper angles whereby to afford an efficient cutting action when presented to the face of the user.

Other objects and advantages to be derived from the use of my improved safety razor will appear from the following detail description and the claims, taken with an inspection of the accompanying drawing, in which:

Figure 1 is a front elevational view of a safety razor embodying the improvements of my invention;

Fig. 2 is a fragmental perspective view of the same;

Fig. 3 is a transverse sectional view taken on the line 3—3 of Fig. 1;

Fig. 4 is an enlarged sectional view taken on the line 4—4 of Fig. 1;

Fig. 5 is an enlarged detailed sectional view of one of the blade retainers;

Fig. 6 is an elevational view of a blade holder for honing; and

Fig. 7 is a fragmental rear elevational view of the blade supporting frame.

Referring more particularly to the drawings, wherein similar characters of reference designate like and corresponding parts throughout the various views, I provide a frame having angularly related rectangular

wings, formed of a single blank of material connected by a strip 3. The wings 1 and 2 are arranged in relatively angularly related planes as well as having their longitudinal axes in right-angular relation. The inner longer edges of the wings 1 and 2 are provided with a plurality of tongues forming guards 4 and 5.

A pair of arms 6 and 7 are connected to the back faces of the wings 1 and 2, said arms 6 and 7 being twisted together as at 8 to form a handle. I do not limit myself to this form of handle, the same merely being shown to indicate one type of handle which may be employed.

The blades are designated 9 and 10, the same being provided with the usual bevel portions 11 and 12, respectively, to provide the cutting edges said blades being receivable on the wings 1 and 2, supporting lugs 13 and 14 carried by the wings at the upper and lower portions thereof, serving to receive the blades and guide the same into operative position. The lugs 14 are provided with enlarged portions 15 subjacent the blade whereby to support the latter in spaced relation to the wings, this being best shown in Fig. 5. It will be seen that the lugs 14 are disposed at the lower corners of the wings to prevent displacement of the blades in that direction.

The blades are clamped in position on their respective wings by means of holders 16 and 17. The holders are identical in construction and I will therefore describe but one of the same shown in Fig. 3. The holder is provided with a cylindrical outer surface and a square opening indicated at 18, a pair of spaced tongues 19 extending from the holder and embracing the blades. The tongues 19 are riveted as at 20 to the blades. Each of the blades and tongues are provided with alining elongated openings forming slots 21 to accommodate the shank of bolts 22, said bolts having flat heads and wing nuts 23, the wing nuts being located on the back of the wings.

The blades 9 and 10 are so relatively placed upon the wings that one marginal edge of the blade 9 is disposed in longitudinal alinement with the inner end of the bevel 12 of the blade 10 so that in use the path of movement of the blade 10 overlaps the path of movement of the blade 9 insuring complete removal of the hair and leaving no streaks. The blades are arranged slightly

in spaced relation as at 24 to prevent spoiling the cutting edge of the blade 9.

A bolt 25 extends through the strip 3 and is provided with a flat head 26, the inner 5 surface of the head being beveled as at 27 to more readily grip the adjacent portions of the blades 9 and 10 and retain the same in position on the wings. A wing nut 28 is carried by the bolt 25. An enlargement 29 10 formed on said strip 3 serves to raise the blades 9 and 10 from the wings 1 and 2, similarly to the enlargement 15 hereinbefore referred to.

A rearwardly directed flange 30 is formed 15 on the upper end marginal edges of the wings 1 and 2 and on the strip 3 to deflect the lather downwardly onto the rear surface of the wings and prevent the same from reaching a person's face while in course of 20 shaving.

A holder for the blades 9 and 10 when being honed is shown in Fig. 6, the same including a handle 31 having a shank 32 provided with a squared portion 33 for insertion 25 into the squared openings 18 of the holder 16. An annular collar 34 is formed on the squared portion 33, and a bolt 35 is provided in one end of said squared portion to clampingly engage the blades and firmly 30 retain the same in position for honing.

It will be seen that in use when the blades are drawn down over the face of the user a slanting cut will be afforded instead of a straight cut, thereby rendering more efficient 35 the operation of the razor and preventing injury to the face of the user. Any part of the face may be reached by my improved razor, the angular relation of the blades as well as their arrangement in angularly 40 related planes serving to provide a more efficient cutting operation. The provision of the holders 16 not only afford means for holding the blades for honing but also serve as guides when using the razor, the same 45 serving to dispose the blades at the proper angle to the face. The blades and wings are cut away as at 36 so that when starting to cut along the side of a person's face the corners of the blades will not cut the user's 50 ear. I desire to lay particular stress upon the arrangement of the blades both with regard to their planes and longitudinal axes, this being the principal feature of my invention. It will be seen that the blades are 55 supported at three points and are clamped at two points each so that accidental dislodgment of the blades when in use is practically impossible. It will be readily ap-

parent to those skilled in the art that in the provision of my improved safety razor 60 I have afforded a device which is exceedingly simple in construction, efficient in operation as well as cheap to manufacture and sell.

From the above description taken in connection with the accompanying drawing, it 65 is thought that a clear and comprehensive understanding of the construction, operation and advantages of my invention may be had, and while I have shown and described the device as embodying a specific structure, 70 I desire that it be understood that such changes may be made in said structure as do not depart from the spirit and scope of the invention as claimed.

Having thus fully described my invention, 75 what I claim as new and desire to secure by Letters Patent, is:—

1. In a safety razor, the combination of a supporting frame including a pair of wings having their longitudinal axes relatively at right angles, a plurality of blades disposed on said wings, said blades having enlargements provided with elongated openings, and means passing through said wings and said enlargements to clampingly engage 85 the blades and retain the same upon said wings.

2. In a safety razor, the combination of a supporting frame, handles extending therefrom, said frame being formed with 90 wing portions, said wings having their longitudinal axes relatively at right angles, a plurality of blades to be disposed on said wings, a bolt extending through said frame to engage the adjacent corners of said blades, 95 said corners being in offset relation to permit the path of travel of one blade to overlap that of the other, and a deflecting flange formed on said wings at the upper marginal edge thereof.

3. In a safety razor, the combination of supporting frames including a pair of wings having their longitudinal axis relatively at right angles, a strip connecting said wings adjacent their outer edges, a plurality of 105 blades disposed on said wings, a holder for said blades, a pair of spaced tongues extending therefrom adapted to embrace the blades, means for securing the blades to said tongues, and a bolt member passing through 110 said wings in said holder to clampingly engage the blades and retain the same upon said wings.

In testimony whereof, I affix my signature hereto.

AVARY B. CARROLL.
